FOOTBALL DOWN MARKER

Glenn C. Cooper, Oceanway, and Gustave B. Ludwig, Jr., and Richard F. Fromhart, Jacksonville, Fla.

Application May 12, 1953, Serial No. 24,965

Term of patent 14 years

(Cl. D34—5)

To all whom it may concern:

Be it known that we, Glenn C. Cooper, Gustave B. Ludwig, Jr., and Richard F. Fromhart, citizens of the United States, residing, respectively, at the unincorporated community of Oceanway, Duval County, at Jacksonville, and at Jacksonville, Florida, have jointly invented a new, original, and ornamental Design for Football Down Marker, of which the following is a specification, reference being had to the accompanying drawing, forming a part hereof.

Fig. 1 is a front perspective view of a football down marker, showing our new design.

Fig. 2 is a fragmentary rear elevational view thereof, the bottom portion being broken away for convenience of illustration; and

Fig. 3 is a bottom plan view thereof.
The drawing figures are lined for color.

We claim:

The ornamental design for a football down marker, as shown and described.
